UNITED STATES PATENT OFFICE.

OLAF N. LINDE AND ANDREW LINDER, OF LINDBERG, WASHINGTON.

INKSTAND.

1,297,877.

Specification of Letters Patent. Patented Mar. 18, 1919.

Application filed June 6, 1917. Serial No. 173,204.

To all whom it may concern:

Be it known that we, OLAF N. LINDE and ANDREW LINDER, citizens of the United States, residing at Lindberg, in the county 5 of Lewis and State of Washington, have invented certain new and useful Improvements in Inkstands; and we do hereby declare the following to be a full, clear, and exact description of the invention, such as 10 will enable others skilled in the art to which it appertains to make and use the same.

This invention relates to stationery, and more particularly to ink stands.

It is one of the objects of the present invention to provide an ink stand combining one or more ink wells and a penholder support, the latter being adapted to automatically control the opening and closing of the ink wells by the deposit of penholders on 20 or the removal of penholders from the penholder support.

Another object of the invention is to provide for the adjustment of the penholder support so that its balance may be varied to 25 compensate for the difference in the weight of a penholder or penholders which may be applied to the support so that the automatic closure or opening of the covers of the ink wells may be provided for in use of penholders or the like of different sizes, weight 30 and number.

Another object of the present invention is to provide means for controlling the dip of a pen into the ink well, and a further object of the invention is to provide a removable ink cell or cells in combination with a base for the stand, whereby the ink may be replenished in the ink cell without affecting the adjustment of the dip controlling device, irrespective of the position of the cover 40 or closure for the ink well.

With these and other objects in view the present invention consists in an ink stand comprising a suitable rack or support to receive penholders or the like, and a peculiar construction and arrangement of ink cells and covers therefor, which latter are controlled by the deposit of penholders on or the removal thereof from the penholder support.

One form of the invention is described

in the following specification and illustrated in the accompanying drawing, in which:

Figure 1 is a perspective view of the ink stand showing the support as carrying a 55 plurality of penholders, the balance adjusting means having been set to provide for the opening, as shown, of the covers of the ink wells upon the removal of a penholder.

Fig. 2 is a cross section on line 2—2 of 60 Fig. 1, but showing the covers closed.

As here illustrated, the ink stand involves a base 2 which may be made of suitable material and of the desired size, form and material. The base is represented as being of 65 rectangular form in the present construction, and is provided with a plurality of chambers 3 opening upwardly from the bottom of the base 2 and having relatively small mouths 4, at the upper portions adjacent the top of the base, which may be formed through either integrally or separately formed mouth portions 5, the mouths 4 being indicated as of downwardly converging outline to facilitate the entrance of 75 a pen to the ink well. Suitably secured to the top portions 5 of the base or chambers 3 there is provided in the present instance covers 6, one for each of the mouths 4, these covers being shown in the form of plates of 80 suitable material and form which are hingedly connected at 7 so that they may be swung upwardly in position to open the cells or swung downwardly to overlap the top portions 5 of the cells.

One of the important features of the present invention resides in the provision of means for automatically controlling the operation of the covers, and incorporates a suitable form of penholder support comprising in this instance a pair of parallel arms 8 which are pivoted centrally upon a shaft or pivot 9 mounted in upright bearings 10 which may be of suitable design and construction and are here shown in the form of 95 inverted U-shaped members 11, the tops of which are depressed or formed with recesses as at 12 to afford support for extra penholders, pencils or the like, as may be desired. The arms 8 of the penholder support may be connected in any suitable manner, and are arranged to project forwardly 100

over the covers 6 of the ink well and are here connected at their rearwardly extending portions by a transverse bar 13 which in part performs the function of being a weight to somewhat counterbalance the forwardly projecting arms 8 of the support. The arms 8 are shown as provided with concaved upper edges to form a convenient recess to receive and support one or more penholders, as shown in Figs. 1 and 2, the deposit of which on or the removal of which from the support is designed to control the opening or closing of the covers of the ink well. Thus when a single penholder is deposited on the arms 8 this will be sufficient to cause the arms to swing down and through their connections 14 to the covers 6 cause the covers to be lowered, and, conversely, when the penholder is removed from the swinging supporting arms 8 the overbalanced arms will rise and automatically lift the covers to open the wells. While a plurality of ink wells are here shown for the purpose, for instance, of receiving different colors of ink, it is obvious that only one well may be utilized. When a plurality of ink wells are incorporated in the ink stand to receive inks of different colors, ordinarily there would be a different penholder for each different color of ink, and these penholders would be normally deposited upon the support, and for the purpose of providing for the excess weight of a plurality of penholders, and also for providing for the varying of the balance of the pen support in accordance with the weight of the penholder or penholders mounted on the support, suitable weight-adjusting means is provided. This adjustment may comprise, for instance, a weight 15 which is shown as provided with a set screw 16, the weight being adjustable upon and along one of the rearwardly extending arms of the support, as shown in Fig. 1.

Another feature of the invention resides in the provision of means for controlling the depth of a pen into the ink well, and in the form shown this means comprises a stop plate 17 extending downwardly into the well below the cover 6, the plate having an upwardly extending shank 18 disposed adjacent to one side of the ink well, and which shank may be offset as at 19 and provided with a yoke or slide portion 20 which in this instance embraces one of the upright posts of the U-bearing 11 and is vertically adjustable along the bearing to the desired position at which it is intended to limit the insertion of a pen into the well. The plate may be held at its adjusted position through any suitable means, and in this instance there is attached to the upright member of the U-bearing a spring 21 which frictionally engages an adjacent portion of the yoke 20 and thereby secures the temporary adjust-

ment of the stop plate at the desired position.

A further feature of the invention resides in the provision in an ink stand, of removable cells which are capable of being removed from the base of the stand without interfering with the adjustment of the pen stop plate 20, and without requiring the removal or adjustment of the cover 6 of the wells, and to that end there is inserted in the chambers 3 of the base 2 suitably shaped and formed cells 22, these being adapted to fit upwardly through the open bottom of the chamber into which it is to be inserted, and is held therein through any suitable fastening device, as, for instance, a draw slide 23 which is insertible through a front aperture 24 formed in the lower portion of the base 2, the rear end of the slide being adapted to enter and bear in a seat 25 on the opposite wall of the chamber 3. Obviously there may be provided as many of the ink well receiving chambers as is desired, and any suitable means may be employed for retaining the removable cells in position in the wells.

There may be secured at any suitable position upon the base 2 an ink wiper 26 in the form of a piece of cloth of suitable properties which may be removably clamped beneath a wiper holder 27 shown in the form of a transverse bar appropriately connected to the portion of the base of the stand upon which the wiper is to be mounted. After the piece of cloth or wiper 26 is soiled it may be thrown away and a new piece readily fitted in position beneath the holder 27. If desired the top of the base 2 may be provided with a sunken portion 28 to receive pins, pen nibs, paper fasteners or any other small devices which may be desired to have handy.

What is claimed as new is:

1. A combined pen-rack and ink-well comprising a base having well pockets, covers hingedly mounted to cover and uncover the pockets; parallel standards on the base having each a top bar to mutually support penholders and pencils or like shaped bodies laid from one to the other; a rock shaft supported in the front elements of the standards; a pen carrier comprising a pair of lever arms mounted on the shaft and having concaved forwardly extending ends to receive penholders, the rear portion of the levers extending between the standards and below top bars thereof and being rigidly connected; a weight slidably mounted on the rear end of one lever; and links connected to the front ends of the levers and to the swinging edges of the respective covers; whereby the weight of a penholder on said levers will close the covers.

2. The combination, in an ink-stand, of a base having a well; a lid hinged to cover

and uncover the well; a pair of substantially horizontal, parallel levers pivoted intermediate their ends on a rock shaft, the front arms of the levers concaved to mutually support a penholder; slideable means on one of the arms for overbalancing the front arms; and a link connected at one end to an adjacent arm and at the other to the

lid so that it will be closed by the weight of a penholder applied to the front arms, the lever being rigidly connected to act in unison.

In testimony whereof we affix our signatures.

OLAF N. LINDE.
ANDREW LINDER.
